FIG. 1 is a perspective view of a glass door embodying my new design;

FIG. 2 is a front view of the door shown in FIG. 1;

FIG. 3 is a side view of the door shown in FIG. 2;

FIG. 4 is a top view of the door shown in FIG. 2;

FIG. 5 is an enlarged view of a portion of the bottom left corner of the door shown in FIG. 2;

FIG. 6 is a view taken as indicated by the lines and arrows VI—VI in FIG. 2;

FIG. 7 is a perspective view of another door embodying my new design;

FIG. 8 is a front view of the door shown in FIG. 7;

FIG. 9 is a side view of the door shown in FIG. 8;

FIG. 10 is a top view of the door shown in FIG. 8;

FIG. 11 is an enlarged view of a portion of the bottom left corner of the door shown in FIG. 8;

FIG. 12 is a section taken as indicated by the lines and arrows XII—XII in FIG. 8;

FIG. 13 is a perspective view of another door embodying my new design;

FIG. 14 is a front view of the door shown in FIG. 13;

FIG. 15 is a side view of the door shown in FIG. 14;

FIG. 16 is a top view of the door shown in FIG. 14;

FIG. 17 is an enlarged view of a portion of the bottom left corner of the door shown in FIG. 14; and

FIG. 18 is a section taken as indicated by the lines and arrows XVIII—XVIII in FIG. 14.

In the figures, the oblique shading indicates glass. The back view of the doors shown is the same as the front view. The dashed line portion showing an opening in the wall in FIGS. 1, 7, and 13, is included for the sole purpose of providing an environment for the door and is not to be considered a part of the design.

I claim:

The ornamental design for a glass door, as shown and described.
